UNITED STATES PATENT OFFICE.

HENRY J. DOCKENDORF, OF MINNEAPOLIS, MINNESOTA.

PRINTER'S QUOIN.

992,485.

Specification of Letters Patent. Patented May 16, 1911.

Application filed December 30, 1910. Serial No. 600,149.

To all whom it may concern:

Be it known that I, HENRY J. DOCKENDORF, a citizen of the United States, residing at Minneapolis, in the county of Hennepin and State of Minnesota, have invented 5 certain new and useful Improvements in Printers' Quoins; and I do hereby declare the following to be a full, clear, and exact description of the invention, such as will enable others skilled in the art to which it 10 appertains to make and use the same.

My invention has for its object to provide an improved printer's quoins used in locking a form within a chase and, to this 15 end, the invention consists of the novel devices and combinations of devices herein-after described and defined in the claims.

In the accompanying drawings which 20 illustrate the invention, like characters indicate like parts throughout the several views.

Referring to the drawings, Figure 1 is a plan view of the improved quoins shown in working position for locking a form within a chase, some parts being broken away and other parts being shown in section; Fig. 2 is a plan view of the improved quoins, on an enlarged scale, removed from working position, some parts being broken away and other parts being sectioned; Fig. 3 is a longitudinal vertical section taken on the line $x^3 x^3$ of Fig. 2; Fig. 4 is a transverse vertical section taken on the irregular line $x^4 x^4$ of Fig. 3; Fig. 5 is a detail view in perspective; Fig. 6 is a plan view showing a 25 slightly modified form of the improved quoins with some parts broken away; Fig. 7 is a longitudinal vertical section taken on the line $x^7 x^7$ of Fig. 6; and Fig. 8 is a transverse vertical section taken on the line $x^8 x^8$ of Fig. 7.

The numeral 1 indicates a portion of an ordinary chase and the numeral 2 indicates a portion of a form, consisting of printers' type, not shown, and furniture, locked without 30 in the chase by means of the improved quoins.

Referring to the improved quoins, the numeral 3 indicates a cam mounted for a limited rotary movement in a horizontal plane within a support consisting of a top 35 bar 4 and a bottom bar 5. The top bar 4 is considerably thicker than the bottom bar 5 and is placed upon the bottom bar 5 and detachably secured thereto by means of machine screws 6 loosely seated in the bar 4 with their heads countersunk therein, and 40 having screw-threaded engagement at their

lower ends with the bar 5. The cam 3 works within a seat 7 formed in and extending transversely through the under intermediate side of the bar 4 and is provided with a 45 plurality of ratchet teeth 8, and a vertical hub 9 which extends on both sides of the cam 3. At its lower end, the hub 9 is loosely mounted in a depressed bearing seat 10 formed in the upper surface of the bar 5, and 50 the upper end of the hub 9 is loosely mounted in a bearing seat 11 formed in the bar 4 which extends completely through the same. The top of the hub 9 lies flush with the 55 upper surface at the top bar 4 and is provided with an angular key seat 12 which, preferably, extends nearly but not quite the full depth of the hub 9, as shown in Fig. 3. Detachably mounted in the key seat 12 is a 60 cam operating key 13 provided with a square 65 shank 14 which closely fits within the key seat 12.

Means for locking the cam 3 in various set positions is provided in the form of a sliding lock pawl 15, for engagement with 70 the ratchet teeth 8 of the cam 3. The lock pawl 15 is provided with a rearwardly extended rack bar 16 which, together with the lock pawl 15 is mounted to slide upon the upper face of the bar 5 within an inverted 75 T-shaped seat 17 formed in the under surface of the bar 4. This seat 17 is provided with an intermediate portion which extends upward through the top of the bar 4 and within which is mounted a segmental pinion 19 that 80 meshes with the teeth of the rack bar 16, for moving the lock pawl 15 into and out of engagement with the ratchet teeth 8. The pinion 19 is loosely mounted on a horizontally extended bearing pin 20, the ends of 85 which are mounted in the bar 4 on opposite sides of the seat 18. An operating arm 21 is integrally formed with, or otherwise rigidly secured, to the segmental pinion 19 and is adapted to be seated, when the lock 90 pawl 15 is in engagement with the ratchet teeth 8, in a seat 22 formed in the upper surface of the bar 4 and extending from the seat 18 to the adjacent end of the bar 4. Said seat 22 is of such depth as to permit 95 the upper surface of the arm 21 to lie flush with the upper surface of the bar 4. The free end of the arm 21 is bent downward at 100 23, to form a finger piece which closely engages the end of the bar 4 when the arm 21 105 is seated in the seat 22.

Referring to the modification shown in

Figs. 6, 7 and 8, the pawl 15 is provided with a rearwardly inverted T-shaped extension 24 mounted for sliding movement together with the pawl 15 upon the upper surface of the bar 5 and within a correspondingly shaped seat 25 formed in the under surface of the bar 4. An upwardly projecting threaded stud 26 is secured to the extension 24 and works through a slot 27 extending from the upper surface of the seat 25 through the bar 5 to an open seat 28 formed in the bar 5 and within which works a thumb nut 29 having threaded engagement with the upwardly projecting ends of the stud 26. As is evident, by tightening the thumb nut 29 on the stud 26, the extension 24 is frictionally held in the seat 25 for locking the pawl 15 in engagement with the ratchet teeth 8 of the cam 3. For the purpose of illustrating the above invention, only one printer's quoин has been shown in the drawings, but in actual practice, it will ordinarily take several of the devices to properly lock the form within the chase.

25 What I claim is:

1. In a printer's quoин, the combination with a support comprising a pair of detachably connected plates, of a cam mounted between said plates and having hubs ro-

tatively mounted therein, one of said hubs 30 projecting through the plate in which it is mounted and provided with a key seat, a sliding lock bar mounted for toothed engagement with said cam, and means for positively locking said lock bar in an operative 35 position, substantially as described.

2. In a printer's quoин, the combination with a support comprising a pair of detachably connected plates, and a clamping member having laterally projecting lugs arranged to embrace the ends of said plates, of a cam mounted between said plates for action on said clamping member and having hubs rotatively mounted in said plates, one of said hubs projecting through the plate in 40 which it is mounted and provided with a key seat, a sliding lock bar mounted for toothed engagement with said cam, and means for positively locking said lock bar in an operative position, substantially as 45 described.

In testimony whereof I affix my signature in presence of two witnesses.

HENRY J. DOCKENDORF.

Witnesses:

ALICE V. SWANSON,
HARRY D. KILGORE.
